Primary Examiner — Ricky Pham(74) Attorney, Agent, or Firm — Mei & Mark LLP; Krystyna Colantoni(57) CLAIM

I claim the ornamental design for a fork or spoon handle, as shown and described.

DESCRIPTION

FIG. 1 is a perspective view of a fork showing my new design;
FIG. 2 is a front view thereof;
FIG. 3 is a rear view thereof;
FIG. 4 is a top view thereof;
FIG. 5 is a bottom view thereof;
FIG. 6 is a right side view thereof;
FIG. 7 is a left side view thereof;
FIG. 8 is a perspective view of a spoon showing my new design;
FIG. 9 is a front view thereof;
FIG. 10 is a rear view thereof;
FIG. 11 is a top view thereof;
FIG. 12 is a bottom view thereof;
FIG. 13 is a right side view thereof; and,
FIG. 14 is a left side view thereof.
The broken lines in the drawings are for illustrative purposes only and form no part of the claimed design.
